AUTOMATIC WORK DRIVING DEVICE

Harold E. Balsiger, Waynesboro, Pa., assignor to
 Landis Tool Company, Waynesboro, Pa., a corporation of Pennsylvania

Application November 10, 1932, Serial No. 642,101

6 Claims. (CL. 82—40)

This invention relates to work holding and driving mechanism and its object is to provide a work drive device which will operate to hold the work correctly and drive it correctly regardless of certain inaccuracies either in the shape or in the position of the work.

A further object is to provide a work driving device which is automatically operated and in which the work may be placed without stopping rotation of the headstock.

Further objects and advantages will become apparent from the description which follows.

Referring to the accompanying drawings which are made a part hereof and on which similar reference characters indicate similar parts,

Figure 1 is a front view of the device with a cover plate removed,

Figure 2, a section on line 2—2 of Figure 1,

Figure 3, a section on line 3—3 of Figure 1,

Figure 4, a section similar to Figure 3 showing the device clamped on work which is neither straight nor concentric,

Figure 5, a face view of Figure 4,

Figure 6, a front view showing a relatively large piece of work in position with the device in clamped or driving position,

Figure 7, a view similar to Figure 6 with the work in unclamped position,

Figures 8, 9, 10 and 11 are detail views of the several parts of the chuck,

Figure 12 is a side elevation of friction means for operating the device, and

Figure 13, a side elevation showing a foot pedal control for operating the device.

In the drawings numeral 20 indicates a face plate which is carried by a footstock spindle 19. The spindle may be either of the live or dead spindle type, that shown being preferably of the dead spindle type. A driving ring 21 is secured upon the face plate 20 by means of screws 22. The ring 21 also carries pins 23 upon which are mounted rollers 24 which rollers are adapted to drive the work holding dog 25 as will be more fully described hereafter. A dog opening finger 26 is pivotally mounted upon a pin 27 which pin is fixed in the ring 21. The driving ring 21 also carries radial pins 28 which are fixed in its periphery. These pins have a flattened surface on their outer ends against which seat springs 29. These springs also seat against surface 30 on the interior of a friction release ring 31. The finger 26 extends through a notch in the ring 21 and engages a notch 32 in the friction release ring 31. A friction band 33 is anchored at 34 to the base of the machine and secured at 35 to an operating

lever 36 which is pivotally attached to the bed of the machine at 37. The lever 36 is operated by means of a foot pedal 38 and a connecting link 39.

The work driving dog 25 has two opposed notches 40 in which the driving rollers 24 engage. The dog 25 is loosely fitted within the driving ring 21 to allow for movement of the dog to clamp work which is out of parallel with the axis of the center 19 or which may not be perfectly round. The dog 25 has a block 41 secured to one face by means of a pin 42. The inner end of this block is V-shaped so as to engage a work piece 51. A cooperating clamping jaw 43 is pivotally attached by a screw 44 to the dog and is urged toward work engaging position by means of a spring 45. The spring 45 is positioned about suitable guide pins 46 to hold it in place. When the dog is in assembled position the dog opening finger 26 fits loosely between clamping jaw 43 and a surface 47 on the dog with the driving rollers 24 positioned loosely in the notches 40. A cover plate 48 is held in position by screws 49 to hold the entire assembly together, the cover plate being provided with a hole 50 through which the work may enter into the dog or work driving device.

In operation, the parts normally rotate in a counterclockwise direction. When the dog is to be opened to insert work therein or to remove work therefrom the foot pedal 38 is operated. This brings the bands 33 into frictional contact with friction release ring 31 to retard rotation of this ring, the ring 21, however, continues to rotate. Rotation of the ring 21 faster than the ring 31 moves the finger 26 toward the right and thus pushes the clamping jaw 43 away from the surface 47, thus opening the work driving jaws to permit removal of the work or to position new work within the jaws. The friction release ring 31 is moved against the tension of the springs 29. As soon as the foot pedal 38 is released the springs 29 will bring the rings 21 and 31 into such a position that the finger 26 will release the movable dog 43 to allow the parts to assume work clamping position. From the description given it will be apparent that the device may be opened without stopping rotation of the headstock and that the opening is automatic. In Figures 4 and 5 the work piece 51 is not in axial alignment with the work center. The work drive dog 25 is shown in a position at which it has adapted itself to the position of the work, i. e. the dog is not in a plane which is parallel with the face plate 20 and the

ring 21 and the associated parts. This device shows the adaptability of the device.

In Figure 5 the work is shown to be off center, the work driving device has shifted to adapt itself to this position of the work. To adapt the device for use with work of different sizes it is necessary only to change the V-blocks 41 and the movable dogs 43 as shown in Figures 6 and 7. In Figure 6 a relatively short V-block 52 is applied to the dog and a movable jaw 53 having a suitable cut-out portion 54 is pivotally adapted to the dog. In other respects the parts of the device are unchanged.

It will be obvious to those skilled in the art that various changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. A work driving device comprising a spindle, 25 a face plate secured thereon, a driving ring secured to the face plate, a driving dog mounted within the driving ring, said driving dog having opposed notches therein, rollers mounted on the driving ring engageable in said notches for driving the dog from the driving ring, a stationary jaw on the driving dog, a movable jaw cooperating with the stationary jaw for gripping the work, resilient means for moving the movable jaw to work gripping position, a finger mounted on the driving ring movable to engage the movable jaw to release the work, a friction release ring positioned about the driving ring, said friction release ring having a notch into which one end of the said finger engages, the friction release ring being normally rotated with the driving ring during operation of the machine, and a friction brake engageable with the friction release ring to retard its motion, such retardation causing the said finger to move the movable work engaging jaw out of contact with the work, substantially as set forth.

2. A work driving device comprising a spindle, a face plate secured thereon, a driving ring secured to the face plate, a driving dog mounted within the driving ring, said driving dog having opposed notches therein, rollers mounted on the driving ring engageable in said notches for driving the dog from the driving ring, a stationary jaw on the driving dog, a movable jaw cooperating with the stationary jaw for gripping the work, resilient means for moving the movable jaw to work gripping position, a finger mounted on the driving ring movable to engage the movable jaw to release the work, a friction release ring positioned about the driving ring, said friction release ring having a notch into which one end of the said finger engages, the friction release ring being normally rotated with the driving ring during operation of the machine, and a friction brake engageable with the friction release ring to retard its motion, such retardation causing the said finger to move the movable work engaging jaw out of contact with the work, said work engaging dog being loosely mounted in the said driving ring whereby it may align itself with the work which is out of perfect alignment with the spindle and when work is non-

concentric and inaccurate in shape, substantially as set forth.

3. A work driving device comprising a plate having a fixed and a movable work engaging jaw thereon, resilient means for urging the movable jaw to work engaging position, means for supporting and driving said plate, a finger mounted on said last named means engageable with said movable jaw to move it to work releasing position and a friction ring mounted on said driving means and resiliently driven thereby and engageable with said finger when the ring is retarded in its rotation and means for retarding rotation of said ring to release the work.

4. A work driving device comprising a plate 15 having a fixed and a movable work engaging jaw thereon, resilient means mounted on said plate for urging the movable jaw to work engaging position, a plate for supporting and driving said first named plate, means on said last named 20 plate engageable with notches in said first named plate for driving the first plate by the second, means for securing said first named plate against axial movement, said last named means providing sufficient clearance to permit an axial float of 25 the first plate relative to the second plate, a ring mounted on said second plate and resiliently driven thereby, said ring rotating normally with said plates, work releasing means, means on said ring for engaging work releasing means when rotation of said ring is retarded relative to rotation 30 of the said plates and friction means engageable with said ring for retarding its rotation to release the work.

5. A work driving device comprising a driving 35 plate having a pair of axially extending driving pins, a ring mounted upon said plate and having a resilient driving connection therewith, a driven plate having substantially radially extending notches engageable by said pins, said notches being sufficiently large to permit a float of said driven plate with respect to the driving plate, means for holding the plates in axial position with respect to each other, said last named means providing a clearance to permit axial floating of 40 one plate with respect to the other, a movable and a fixed work engaging jaw mounted on the driven plate, resilient means mounted on the driven plate for moving the movable jaw to work engaging position, means on the driving plate engageable with the movable work engaging jaw to move it to work releasing position, said last named means being engageable by said ring to release the work when said ring is retarded in 45 its rotation with said plates and friction means for retarding rotation of said ring.

6. A device of the kind described comprising a floating work driving dog having a movable and a fixed work engaging jaw mounted thereon, a plate for supporting and driving said dog, means 60 on said plate engageable with said movable jaw for releasing the work, means on said dog for holding said jaws in work gripping position, a ring mounted on said plate and being resiliently driven thereby, said ring being engageable with 65 said jaw releasing means upon a retardation of the rotation of said ring with respect to the rotation of the plate, and friction means engageable with said ring for retarding its rotation to release the work.

HAROLD E. BALSIGER.
